US0D1092936S

(12) United States Design Patent (10) Patent No.: US D1,092,936 S
(45) Date of Patent:  Sep. 16, 2025

(54) FOOTWEAR

(71) Applicant: Crocs Trading Company PTE. LTD.,
Singapore (SG)

(72) Inventor: Jessica Lin, Weymouth, MA (US)

(73) Assignee: Crocs Trading Company PTE. LTD.,
Singapore (SG)

() Term: 15 Years

(21) Appl. No.: 29/927,583

(22) Filed: Feb. 5, 2024

(51) LOC (15) Cl. 02-04
(52) U.S. Cl.
USPC D2/969; D2/947

(57) CLAIM

The ornamental design for footwear as shown and described.

DESCRIPTION

FIG. 1 is a top perspective view of footwear;
FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1–7 that are overlaid with a white mask bounded by broken lines represent portions that form no part of the claimed design.

1 Claim, 7 Drawing Sheets
